CLOTH ROLL MOUNTING FOR NARROW
WARE LOOMS

Elbridge R. Holmes, Worcester, Mass., assignor to
Crompton & Knowles Loom Works, Worcester,
Mass., a corporation of Massachusetts

Application April 10, 1950, Serial No. 155,110

6 Claims. (Cl. 139—304)

1

This invention relates to improvements in narrow ware looms and it is the general object of the invention to provide improved means for mounting the cloth roll supporting shafts so they may be readily applied to and removed from the loom.

Many narrow ware looms attain such a length as to make desirable intermediate supports or frames between the loomsides for the take-up and cloth roll mechanisms. In such looms the cloth rolls are ordinarily mounted on several aligned shafts which are supported by bearings carried by the intermediate frames, but in the past these intermediate bearings have been of complicated construction involving several parts and necessitating considerable labor to remove the shaft sections for the purpose of unwinding the cloth and then returning the shaft sections to the loom.

It is an important object of the present invention to provide a bearing for two adjacent ends of cloth roll shafts mounted on an intermediate support or frame and held in position against endwise motion relative to the shafts by a single retaining means carried by the intermediate frame. The bearings preferably have non-circular frustro-pyramidal cups or the like to receive similarly formed ends or gudgeons of the shaft sections, and the cups are so formed as to free their gudgeons readily when the opposite end of the shaft is swung forwardly.

The cloth rolls of narrow ware looms may either be loose on their supporting shafts and be turned by a belt or the like turned from a loom shaft, or they may be equipped with a friction drive for their supporting shafts to be turned as the latter are rotated. When the latter manner of driving the cloth rolls is utilized a gearing mechanism is employed at each end of the loom and half of the aligned shafts are driven from one end and the other half from the opposite end. It is a further object of the invention to mount the adjacent ends of shafts driven from opposite ends of the loom in a central bearing made of two saddle or bearing parts which are alike, one part for each shaft end, and clamp the two parts together and to an intermediate frame. In carrying out this feature of the invention each half or part of the central bearing will have a gudgeon or part of the central bearing will have a gudgeon rotatable in the center intermediate frame and another part formed as an open slot bearing to permit forward removal of the associated shaft.

With these and other objects in view which will appear as the description proceeds, the invention resides in the combination and arrangement of parts hereinafter described and set forth.

In the accompanying drawings, wherein a con-

venient embodiment of the invention is set forth,

Fig. 1 is a front elevation showing the invention applied to a loom assumed to have considerable length,

5 Fig. 2 is an enlarged vertical section on line 2—2, Fig. 1, showing the central bearing,

Fig. 3 is a horizontal section on line 3—3, Fig. 2,

Fig. 4 is an enlarged vertical section on line 4—4, Fig. 1, showing the bearing for a cloth roll shaft at the right end of the loom,

10 Fig. 5 is a horizontal detail section on line 5—5, Fig. 4,

Fig. 6 is an enlarged horizontal section on line 6—6, Fig. 1 showing a bearing so constructed as to afford driving relation between the adjacent ends of two cloth roll shafts, and

15 Figs. 7 and 8 are vertical sections on lines 7—7 and 8—8, respectively, of Fig. 6.

Referring particularly to Fig. 1, the loom has 20 at the ends thereof primary loom frames 10 between which are located five intermediate frames 11—15. These frames may be held in fixed position in any approved manner as is customary in the manufacture of narrow ware looms of considerable width.

25 Each of the several webs or fabrics 20 is wrapped around a take-up roll 21 and then leads to a cloth roll 22. As indicated in Fig. 1, the loom is considered as being divided transversely into four sections I, II, III and IV, and the cloth rolls of these sections are mounted on cloth roll shafts 25, 26, 27 and 28, respectively. These shafts are aligned lengthwise of the loom and the cloth rolls are driven frictionally by their respective shafts and tend always to turn a little faster than is required to take up the cloth delivered to them by their take-up rolls.

30 The loom has two take-up mechanisms 30 and 31 located respectively at the left and right ends thereof which drive gears 32 and 33, respectively. Gear 32 is secured to shaft 25 and gear 33 is secured to shaft 28.

35 As shown in Fig. 4 the shaft 28 has secured thereto a collar 35 which engages the inner or left end as viewed in Fig. 1 of a bearing 36 on frame 15 having upper and lower arms 37 and 38 which define between them a forwardly opening slot bearing 39 for shaft 28. The latter extends through the bearing slot 39 so that the gear 33 40 may be attached thereto, and is normally held in the position shown in Fig. 4 by a removable pin 40 passing down through the arms 37 and 38 in front of the shaft 28. When it is desired to move 45 the right end of shaft 28 forwardly the pin 40 is 50

55 the right end of shaft 28 forwardly the pin 40 is

removed and the shaft swung in a frontward direction out of the slot 39.

It is desirable that shaft 28 be able to drive shaft 27 and means for accomplishing this result is shown in Figs. 6, 7 and 8, where it will be seen that a bearing member 45 having a cylindrical periphery 46 fits into a hole or bearing 47 in the intermediate frame or support 14. This bearing has oppositely opening bearing cups 48 and 49, respectively, which are preferably frusto-pyramidal to receive similarly formed gudgeons 50 and 51 on the shaft sections 28 and 27, respectively.

A positioning screw 52 is tapped through the forward part of the intermediate frame 14 and extends into a slot 53 formed peripherally in the bearing 45 to limit motion of the latter transversely of the frame 14 and longitudinally of the adjacent shaft sections. The bearing cups 48 and 49 are coaxial so that the shaft sections 27 and 28 are held with their axes aligned.

When the right end of shaft 28 is moved forwardly in slot 39 as already described the gudgeon 50 because of its shape will be able to unseat itself readily from its bearing 48 in the collar 45 without cramping and without subjecting the collar to any strain which might break it. Likewise, after the cloth has been removed from the rolls 22 the shaft 28 can be replaced first by inserting its gudgeon 50 into the bearing 48 and then moving it endwise to the left, Fig. 1, until the collar 35 is against the intermediate frame 11, after which the shaft will be inserted into its end bearing and pin 40 replaced.

The left end of shaft 25 and the adjacent ends of this shaft and shaft 26 may be mounted in a manner similar to that already described for the shaft sections 27 and 28. The two aligned shafts 27 and 28 will be driven by gear 33, and in like manner the aligned shaft sections 25 and 26 will be driven by gear 32.

The adjacent ends of shafts 26 and 27 are mounted for rotation as shown in Figs. 2 and 3. The intermediate frame 13 has drilled therethrough a hole 60 serving as a bearing for shaft supports or saddle bearings 61 and 62, see Fig. 3, which collectively may be considered as a central bearing. The two saddles 61 and 62 are alike but will be described as two separate parts. The saddles 61 and 62 have slot bearings 63 and 64, respectively, opening forwardly for reception of their associated shaft sections and saddle 61 has a gudgeon 65 extending into one side of bearing 60 and saddle 62 has a gudgeon 66 fitting into the other side of the bearing.

The gudgeons 65 and 66 have parallel walls 67 and 68, respectively, extending along one side of their respective slots 63 and 64. A clamping screw 69 extends through wall 68 and is tapped into wall 67. The bearing members 61 and 62 have shoulders 70 and 71, respectively, which can be and preferably are clamped tightly against adjacent faces of the intermediate frame 13 by screw 69, the gudgeons 65 and 66 being spaced slightly to permit this clamping. The gudgeons project beyond their shoulders a distance slightly less than half the width of bearing 60, see Fig. 3.

A screw 72 is tapped through the forward part of intermediate frame 13 in front of bearing 60 and is set up against flat surfaces 73, Fig. 2, on the two gudgeons to prevent them from turning in the bearing 60 if it is not desired to rely wholly upon screw 69 to clamp the saddles in place. The latter screw holds the

saddles together so that the single screw 72 can engage both surfaces 73. Rods 75 and 76 similar to pin 40 may be provided for their corresponding shaft sections and ordinarily hold the shafts in their open bearings 63 and 64. When removed these pins 75 and 76 permit forward removal of the adjacent ends of their corresponding shafts.

The two saddles 61 and 62 are alike and each is symmetrical about a plane passing through the axis of its gudgeon and also the longitudinal axis of its slot bearing. The shoulders are formed like a horse shoe and their arm parts 77 and 78 which define the slots are joined by a rounded part 79, see Fig. 2. As shown in Fig. 3 one of the saddles has been inverted with respect to the other saddle in the direction of the length of the shafts 27 and 28 before being fitted to the frame 13.

If it be desired to remove shaft section 27 for instance its pin 76 will be removed and the left end thereof as viewed in Fig. 1 will be slid forwardly in the open slot bearing 64 and then moved to the left so that its gudgeon 51 may free itself readily from bearing 49 in the manner already described in connection with the removal of shaft section 28.

It may not be necessary in all instances to employ the set screw 72 as a supplement to the screw 69, but it has been found desirable and when used will not require such a tight setting of the screw 69.

From the foregoing it will be seen that the invention sets forth simple mounting means for aligned cloth roll shafts of narrow ware looms, the bearing 45 as shown in Fig. 6 having tapered cups of non-circular cross section to receive similarly tapered non-circular shaft gudgeons which free themselves from their bearings when the opposite ends of the associated shafts are moved forwardly. It will also be seen that the center bearing is made of two saddle bearings which are alike and one of which is inverted with respect to the other. Each of the saddles or bearing members 61 and 62 has an open slot bearing extending along a gudgeon and wall positioned in the bearing 60. The walls 67 and 68 are formed as parts of the gudgeons 65 and 66 and the two saddles are joined by screw 69 passing through one wall and tapped into the other.

The coupling shown in Figs. 6 to 8 is not claimed herein, but is disclosed and claimed in divisional application Serial No. 318,203, filed November 1, 1952.

Having thus described the invention it will be seen that changes and modifications of the foregoing specific disclosure may be made without departing from the spirit and scope of the invention.

What is claimed as new is:

1. In cloth roll mounting means for a narrow ware loom, a frame intermediate the ends of the loom having a bearing therein the axis of which extends lengthwise of the loom, a pair of aligned cloth roll shafts, a saddle bearing, one on each side of the frame, a gudgeon on each saddle bearing extending into said bearing in the frame, each saddle bearing receiving one of said shafts, and means between the ends of the shafts securing said saddle bearings together.

2. In cloth roll mounting means for a narrow ware loom, a frame intermediate the ends of the loom having a bearing therein the axis of which extends lengthwise of the loom, a pair of aligned cloth roll shafts, saddle bearings each formed

with an open slot bearing located on opposite sides of said frame, each open slot bearing receiving one of said shafts, a gudgeon formed on each saddle bearing extending into said bearing in said frame, and screw threaded means interconnecting said gudgeons and clamping said saddle bearings to said frame.

3. In cloth roll mounting means for a narrow ware loom, a frame intermediate the ends of the loom having a bearing therein the axis of which extends lengthwise of the loom, a pair of aligned cloth roll shafts, one on each side of the frame, a saddle bearing on each side of the frame receiving an end of the adjacent shaft, a shoulder on each saddle bearing extending beyond the bearing in the frame and engaging the adjacent side of the latter, a gudgeon on each saddle bearing extending into the bearing in the frame, and clamping means between the ends of the shafts connecting said gudgeons and holding said shoulders in tight holding engagement with said frame.

4. In cloth roll mounting means for a narrow ware loom, a frame intermediate the ends of the loom having a bearing therein the axis of which extends lengthwise of the loom, a pair of aligned cloth roll shafts, one on each side of the frame, a saddle bearing on each side of the frame having an open slot bearing to receive the end of the adjacent shaft, a gudgeon formed on each saddle bearing extending into the bearing in the frame, and a clamping screw extending through one of said gudgeons and screw threaded into the other gudgeon located between the ends of said shafts and effective when tightened to secure the saddle bearings to said frame.

5. In cloth roll mounting means for a narrow ware loom, a frame intermediate the ends of the loom having a bearing therein the axis of which

extends lengthwise of the loom, a pair of aligned cloth roll shafts, a saddle bearing, one on each side of the frame, a gudgeon on each saddle bearing extending into said bearing in the frame, each saddle bearing receiving one of said shafts, means between the ends of the shafts securing said saddle bearings together, and a set screw in the frame engaging both of said gudgeons and preventing rotation of the saddle bearing relative to said frame.

6. In cloth roll mounting means for a narrow ware loom, a frame intermediate the ends of the loom having a bearing therein the axis of which extends lengthwise of the loom, a pair of aligned cloth roll shafts, saddle bearings each formed with an open slot bearing located on opposite sides of said frame, each open slot bearing receiving one of said shafts, a gudgeon formed on each saddle bearing extending into said bearing in said frame, screw threaded means interconnecting said gudgeons and clamping said saddle bearings to said frame, and a set screw in the frame engaging both of said gudgeons holding said open slot bearing fixed with respect to each other and preventing rotation of said saddle bearings relative to said frame.
